Primary Examiner — Gino Colan(74) *Attorney, Agent, or Firm* — Michael Best & Friedrich LLP(57) **CLAIM**

The ornamental design for a multiport self-burning log, as shown and described.

DESCRIPTION

FIG. 1 is a perspective view of a multiport self-burning log showing my new design;

FIG. 2 is a top view thereof;

FIG. 3 is a bottom view thereof;

FIG. 4 is an elevation view of a first side view thereof;

FIG. 5 is an elevation view of a second side view thereof, opposite the first side;

FIG. 6 is an elevation view of a first end view thereof;

FIG. 7 is an elevation view of a second end view thereof, opposite the first end; and,

FIG. 8 is a cross-sectional view thereof, taken along line 8-8 of FIG. 2.
